SAFETY DEVICE FOR LOCKS

Henry Alberg, Millstadt, Ill.

Application December 21, 1936, Serial No. 116,861
In Canada January 2, 1936

2 Claims. (Cl. 70—424)

The invention relates to improvements in key-hole guards and particularly to an improved guard for completely blocking and covering the key-hole in a door or the like.

An object of the invention is to provide an inexpensive device of the character referred to adapted to be inserted into the key-hole of a lock to prevent manipulation of the latch bolt with improved means to insure its retention over and in a key-hole, and means to prevent unauthorized disengagement of said retaining means.

The foregoing and such other objects of the invention as will appear hereinafter as the description proceeds, will be more readily understood from a perusal of the following specification, reference being had to the accompanying drawing, in which:

Fig. 1 is a perspective view of the device.

Fig. 2 is a fragmentary vertical sectional view 20 through a door showing the device, partially in section, positioned therein prior to locking.

Fig. 3 is a fragmentary view similar to Fig. 2, showing the device locked in position.

Fig. 4 is a front elevational view of the device 25 in locked position.

Fig. 5 is a fragmentary sectional view taken substantially on line 5—5 of Fig. 3.

Fig. 6 is a side elevational view of a device of modified structure.

Fig. 7 is a side elevational view, partly broken away, showing another form of the device locked in place.

The device generally comprises a suitable closure plate, adapted to be placed over the key-hole in one side of the door, having an extension on one face arranged to extend into the key-hole to prevent insertion of a key from the side of the door opposite to that side in which the device is inserted, and suitable means to securely retain and lock the device in place to prevent unauthorized removal thereof.

Referring to the drawing, the key-hole guard, shown in Figs. 1 to 5, inclusive, preferably comprises a substantially rectangular closure plate 11 having an extension 12 formed integral therewith and extending outwardly at right angles from one face thereof. The extension 12 preferably is formed in cross-section, at its free end, to conform substantially to the shape of a key-hole 13 in lock housing 14. A boss 15, countersunk to receive a reduced portion 16 of a collar or hand grip 17, extends outwardly from plate 11 in a direction opposite to that of the extension 12. The reduced portion 16 is also countersunk, as at 55 18, and a pin or stem 19 is secured therein, ad-

jacent one of its ends. The pin 19 extends through the closure plate and has an elongated head 19^a defining oppositely disposed wings 19^b. A compression spring 23, inserted in the countersink 18, normally holds the head 19^a tightly against plate 11. The hand grip 17 and the pin provide means to retain the device in place over the key-hole. 5

To mount the device in place, the elongated head 19^a is positioned in vertical alignment with extension 12, as best shown in Fig. 2. The extension 12 then is inserted into the key-hole 13 and the plate 11 is brought tightly against the associated lock cover plate 22 on the door. The hand grip 17 then is urged inwardly, compressing 15 spring 23, and partially rotated to move the wing portions of the elongated head 19^a on pin 19 into position for engagement with the rear side of the cover plate 24, as best shown in Figs. 3 and 5. The hand grip 17 is suitably spaced from the boss 20 15 to adapt the improved key-hole guard for mounting over key-holes in doors having cover plates of various thickness.

To facilitate alignment of the device with the key-hole, a pin 20 extends from the same side 25 of plate 11 as and below the extension 12, into the key-hole 21.

Means is provided on the device to prevent turning of the hand grip 17 to disengage the elongated head 19^a by the application of a key or 30 tool through the key-hole from the outside of the door. In this embodiment spaced lugs 24 extend from plate 11 adjacent its upper end to provide means to pivotally mount one end of a lock lever 25. The free end of lever 25 preferably has a 35 flared portion 26 on each side. The hand grip 17 has a dovetail longitudinal slot 27 which, when the elongated head 19^a is positioned substantially horizontally, is adapted to engage over the flared portions 26. This engagement is effected by 40 swinging the lever 25 downwardly to position the flared portions 26 in alignment with the dovetail slot 27 while the retaining element is in depressed position. Upon release of the retaining element the slot is carried backwardly to embrace 45 the flared portions 26. Juggling or tampering with the device, through the key-hole from the outside of the door, cannot disengage the lock lever, hence the elongated head 19^a cannot be turned to release the device. 50

To remove the device from the key-hole, the retaining element is pressed, against the action of spring 23, and the lock lever 25 swung upwardly. The retaining element then can be turned to position the elongated retaining head 55

19^a in vertical alignment with the key-hole whereupon the whole device may be removed from the door.

The form of device illustrated in Fig. 6 has 5 one or more radially spaced lugs 28 on the hand grip 17^a each formed with a shoulder 29 at one end to engage over a pin 31 in the lock lever 25^a, when the latter is swung downwardly into locking position.

10 In Fig. 7 the recessed boss 15 on the device has an inwardly directed lug 32 adapted to engage in an L-shaped slot 33—33^a in the hand grip 17. When the elongated head 19^a is substantially vertical and the retaining element 15 pressed inwardly against spring 23, the lug 32 engages in the circumferential portion 33 of the slot. Upon release of the retaining element, after the elongated head has been positioned horizontally, the spring urges the head 19^a tightly 20 against the backface of the cover plate 22 and the lug 32 engages in the longitudinal slot portion 33^a. Hence, the retaining head 19^a cannot be turned to release and remove the device from over the key-hole.

25 It is obvious that the closure plate 11 of the improved key-hole guard entirely covers the key-hole 21 in cover plate 22, thus obstructing vision through the key-hole; and that the extension member 12, conforming substantially to the 30 shape of the key-hole, prevents access being had to the usual latch bolt 34 or to the retaining pin 19 from the side of the door opposite to that in which the device is inserted.

Although exemplary embodiments of the invention have been illustrated in the accompanying drawing and described in detail in the foregoing specification, it is to be understood that various other modifications in detail structure 5 may be incorporated without departing from the spirit of the invention or the scope of the appended claims.

I claim:

1. A device of the character described comprising, in combination, a plate, an extension on said plate adapted for insertion into the key-hole of a lock, yieldably mounted means including a hand grip mounted on said plate adapted to retain the device in place, and a lock lever 15 pivotally mounted on said plate movable into position for locking engagement by said hand grip to lock said retaining means.

2. A device of the character described comprising, in combination, a plate, an extension on 20 said plate adapted for insertion into the key-hole of a lock, a rotatable and yieldably reciprocal element including a hand grip mounted on said plate adapted to retain the device in 25 place, a longitudinal dove-tail groove in said hand grip, a lock lever pivotally mounted at one end on said plate, and an enlargement on the free end of said lever adapted to engage in said groove to lock the retaining element against 30 rotation.

HENRY ALBERG.
